PIPE RACK

Hazen L. Rymal, Refugio, Tex.

Application March 11, 1939, Serial No. 261,297

9 Claims. (Cl. 211—60)

The present invention relates to a rack adapted to be used on the derrick floor of an oil well to support pipe such as casing, drill pipe and tubing, in convenient position for use within the derrick.

One of the principal objects of the invention is to provide a pipe rack which will permit orderly arrangement of the well pipe when stacked, as distinguished from the helter-skelter way of stacking such pipe as now exists.

An important object of the invention is to support pipe on the derrick floor in such manner that fluid and debris therein will drain while the pipe is not in use.

Another object of the invention is to provide a metal rack for supporting pipe as aforesaid, in such manner that lower ends of the pipe will not become injured by contact with the metal of the rack.

A further object of the invention is to provide a pipe rack as aforesaid which will prevent the entrance of wooden splinters or other foreign matter into the circulating system of the well, thus avoiding the fouling of valves, pumps and various other working parts of the well system.

In the drawings, which are illustrative of one form which the invention may take:

Figure 1 is a diagrammatical side elevational view of an oil well derrick showing pipe stacked in one side thereof in accordance with the present invention.

Figure 2 is a diagrammatical plan view of the derrick floor, with the drill racks arranged thereon in position to receive the drill pipe.

Figure 3 is a horizontal sectional view through the derrick on the line 3—3 of Figure 1.

Figure 4 is a diagrammatical plan view of the derrick floor, similar to Figure 2, but showing the pipe racks arranged in a different manner.

Figure 5 is a top plan view of a plurality of pipe racks.

Figure 6 is a central longitudinal vertical sectional view of the pipe racks shown in Figure 5.

Figure 7 is a bottom plan view of the pipe racks shown in Figures 5 and 6.

Figure 8 is an end view of one of the pipe racks.

Figure 9 is an enlarged plan view of a portion of one of the pipe racks, showing one of the pipe receiving means, and

Figure 10 is a vertical sectional view along the line 10—10 of Figure 9, and showing an end of a section of drill pipe positioned on its receiving means.

Throughout the various operations involved in drilling and completing oil wells, it is necessary to insert pipe into and remove it from the well many times.

At the present time, wells have been drilled to a distance of over 13,000 feet. The pipe used, called drill pipe or flow tubing, is made up of relatively short lengths called sections. Each section may be of any arbitrary length such as twenty feet or more.

In running this pipe into the well, one section thereof is inserted until its upper end is just above the derrick floor, after which a section to be added is attached thereto and lowered on into the well, this operation continuing until the desired depth is reached. Pipe is removed from the well in the reverse manner, breaking the pipe into sections as it is taken from the well. Usually the pipe is kept in lengths of three or more sections, and before the pipe is inserted, or after it is removed, it is kept stacked in the side of the derrick convenient for use in the above-mentioned lengths.

It will be understood that these lengths of pipe are quite heavy, and their manipulation during insertion and withdrawal is quite a problem.

It has previously been the custom to support the lower ends of this pipe at the side or in one corner of the derrick on a wooden platform comprising planks of hard wood which are simply laid upon the floor of the derrick. Some operators merely stack this pipe on a pile of old rope.

When pipes are stacked in the manner described above, there is no orderly planned arrangement of the various sections of pipe, and consequently, the stacked pipe often occupies more space than is necessary. Due to the difficult operations which are performed within the derrick during the drilling of a well, space is at a premium, and the importance of an invention which will simplify and make more orderly the stacking of pipe, and which will save as much of the available space as possible, is readily apparent.

Referring to Figure 1, the sides of the derrick are diagrammatically illustrated at 10, and it will be understood that an ordinary derrick may be from one hundred to one hundred and fifty feet in height. The derrick floor is shown at 12, and it is on this floor or platform that the men stand during the performance of operations in inserting pipe into and removing it from the well. At one side of the derrick floor,

at 14, is an arrangement of machinery known as the "draw works." The draw works usually comprise a hoisting drum, a hoisting engine and various reels, and these connect by steel cables with a pulley at the top of the derrick which is known as the "crown block." The various hoisting lines and attachments depend from the crown block down into the derrick, and they carry at their lower ends devices for manipulating equipment into and out of the well. In Figure 1, what is known as an "elevator" 16 is shown depending from the crown block of the derrick. Elevators usually comprise pairs of hinged jaws which grip the pipe beneath an enlarged collar thereof, and support the same as it is being lowered into the well.

The sections of pipe 18 are shown stacked in the side of the derrick in substantially vertical position. They are usually not exactly vertical, but lean against one side of the derrick. The lengths of the pipe are connected by joints 20, and as the present description will use drill pipe as an illustration, these joints are shown as tool joints which are employed to connect together sections of such pipe. The sections of pipe are supported at their lower ends on the drill rack R, and at their upper ends by what is known as a hay rake. The hay rake is only illustrated diagrammatically and is shown comprising a member 22 secured to the frame of the derrick, carrying spaced retaining arms 24 as shown in Figure 3 between which the sections of the pipe are arranged.

Assuming that a portion of the pipe has been inserted into the well, and the time has arrived to add another section thereto, the elevator 16 is lowered until it can be secured beneath the uppermost collar 20 on a particular section. Thereafter, the section of pipe is lifted and its lower end is fitted or threaded into the upper end of the last section which has already been inserted into the well. In the case of drill pipe, the upper collar of the lowermost section will have a tapered threaded female socket, into which is inserted and threaded the tapered threaded male socket at the lower end of the uppermost section of pipe. An illustration of the tapered male portion of the socket is shown in Figure 10. It is obvious that such a joint or connection may be damaged by the presence of sand or other foreign matter in the union.

The threading of the sections together is usually made more rapid in winding a spinning rope around the upper section while it is supported in position by the elevator, and then rapidly pulling this line off the section to cause it to spin or turn on its axis and rapidly thread itself into the socket of the lowermost section. It is desirable to keep the pipe adjacent the union dry and free of mud, to make this spinning operation practical.

In present practices, when the pipe is simply stacked on planks on the derrick floor, the lower end of each section bites into the wood of the planks by reason of the weight of the section, and forms a seal, thus retaining sand, mud and fluid within the lower end of the section. It will be understood that the well pipe is often filled with heavy mud during the drilling and other operations. Hence, when a section of pipe is elevated for connection with that previously inserted into the well, the mud and fluid runs out from the lower end of the section when it is elevated from the wooden platforms, and covers the pipes surrounding the joint, thus making

them wet and slippery, and making the spinning operation impractical and even dangerous. In handling drill pipe, this mud also covers the rotary drilling unit and covers the derrick floor.

5 Furthermore, due to the heavy weight of the sections, they bite into the wooden floor planks breaking splinters therefrom, which splinters get in the joints of pipe as the sections are connected and prevent the forming of a tight union. Such 10 splinters, or pieces of rope if the latter is used, get into the circulating system of the well, causing valves to be disabled by being held off their seats, and fouling pumps and other devices in the system. These splinters may also clog the 15 mud screen of the well. One particular result of such splinters has been found to be in the coring operation, when a core bit is operated at the bottom of the drill string to retain a sample of the formation. A splinter fouling a core barrel 20 ball and seat valve will prevent the retaining of the core sample. Splinters in casing float collar 25 shoes and valves may also interfere with cementing operations, and splinters in the back pressure valve of a drill string may prove to be dangerous in preventing circulation of mud.

The construction of the drill rack is shown in Figures 5 through 10. Each section of the rack comprises a plate 26 provided with a plurality of spaced means to receive and position the lower 30 end of a section of pipe. These means may be in the form of recesses, but I have found the most convenient form to be spaced projections 28 which extend upwardly from the plate 26. The plate 26 is made of metal, such as iron or 35 steel, and is formed with the integral or detachable upwardly extending projections 28. Surrounding said projections, and preferably embedded in the upper face of the plate 26 are relatively soft substantially annular rings 30, which 40 may be composed of such metal as lead, babbitt or the like. These rings may be made of any appropriate material other than metal. The purpose of the rings is to receive the lower edges 45 of the pipe as shown in Figure 10, without injuring the same, it being evident that the relatively hard metal of the pipe will bite into the soft metal ring without injuring the former. The pipe receiving projections are so spaced, as shown in Figure 5, that the tool joints 20 of the pipe, (shown in broken lines), will almost 50 touch each other when the sections of pipe are stacked. Space on the derrick floor is thus conserved. The projections 28 are provided with circularly spaced outside angular cutouts 34, as 55 shown in Figure 9, and extending through the plate 26 within said cutouts, and inside of the soft metal ring 30, are openings 36. These openings provide drainage channels leading from within the ring 30, to drain the pipe when it is supported on the rack. When the lower end of a section of pipe is supported on the rack as shown in Figure 10, the openings 36 are within the bore of the pipe and therefore permit mud and fluid to drain from the interior thereof. While the means for draining the interior of the pipe may be in the form of channels extending from the projections outwardly to the edges of the rack, the most convenient arrangement is to provide openings extending downwardly entirely through the plate 26.

While several rows of projections may be provided on a single plate, I have found it more convenient to provide relatively narrow plates each having a single row of projections as shown in Figure 5, and these plates can be arranged adja-

cent one another in any convenient manner as described in more detail below.

As shown in Figures 6 and 7, the bottom of each plate 26 is provided with a plurality of spaced downwardly depending ribs 38 extending laterally across the plates. These ribs support the plates in spaced relation to the base on which they are positioned, which is the derrick floor, so that mud and fluid which drains from the pipe through the openings 36 can be washed off the derrick floor by such means as the hose and nozzle H shown in Figure 1. At the corners of the plates, the end ribs 38 are provided with downwardly directed pointed projections 40, which serve to bite into the wood of the derrick floor and retain the racks in fixed position.

The ribs 38 depend deeper on one side of the plate than on the other side thereof, as shown in Figure 8, so that the upper face of each plate can be arranged to slant upwardly away from the side of the derrick carrying the hay rake, as shown in Figure 1. This arrangement permits the weight of each pipe section to be applied normal to the upper face of the plate, and permits projections 28 to extend straight up into the pipe sections.

The racks may be in straight integral lengths, or they may be in shorter lengths pivoted together as shown in Figures 4, 5 and 6 to facilitate arranging them in the desired manner on the derrick floor. Referring to Figures 5 and 6, one end of one plate is provided with an upper flange 42, which overlies a lower flange 44 on the adjacent plate, and these flanges are pivoted together by a pin 46, so that they may be adjusted horizontally with respect to one another as desired.

In Figures 2 and 4, the relative location of the rotary drilling unit 48 and the draw works 14 on the derrick floor is shown. The rotary drilling unit includes a drive bushing 50 through an opening in which the drill pipe is inserted, the bushing being rotated through gearing from an adjacent engine and engaging the drill pipe in a well-known manner to cause the same to turn during the drilling operation.

It will be understood that in drilling and completing an oil well, it is necessary to remove the length of drill pipe and insert the same again into the well a number of times in order to perform various necessary operations. As the drill pipe is withdrawn from the well, and broken up into sections, the sections are customarily stacked in the side of the derrick.

Referring to Figure 2, when the first section is to be detached, the elongated rack section 52 is placed on the derrick floor at a convenient location extending between the draw works and the rotary drilling unit at the outside of the derrick platform. The first section of drill pipe is broken off, and while supported by the elevator 16, is pushed over and its lower end engaged with the first projection 54 on the rack 52 adjacent the rotary drilling unit. The upper end of this section is inserted into the space 56 between the outermost pair of arms 24 of the hay rake toward the rotary drilling unit as shown in Figure 3. The next section broken off is similarly disposed over the adjacent projection 58 on the rack 52, and its upper end is disposed in the second space 60 between the arms of the hay rake 24 as shown in Figure 3. Thereafter, succeeding sections are placed on successive projections on the rack 52 working toward the draw works until all of the projections of

this rack are engaged, at which time the inner ends of the spaces between the arms 24 of the hay rake of Figure 3 will all be engaged.

It will be understood that during the above operations, the succeeding racks 62, 64, 66 and 68 shown in Figure 2 need not be in position on the derrick floor, so that the crew can push the sections of pipe over into engagement with the projections on the first rack 52 without having to walk over the projections on the succeeding racks, which would be necessary if the complete rack was made up of a single plate provided with a number of rows of projections.

As sections of pipe are withdrawn, the racks 52, 62, 64, 66 and 68 are successively filled in the manner described above, filling the spaces between the arms 24 of the hay rake in a similar manner.

When it is again desired to build up the drill string as it is again being inserted into the well, the reverse of the procedure outlined above may be followed. That is, sections of the drill pipe may be taken first from the end of the outermost rack 68 adjacent the draw works, working toward the rotary drilling unit 48, and as the pipe sections are taken from each succeeding rack, that rack may be removed, so that, as mentioned above, the crew will not have to walk over the empty racks.

A comparison of Figures 2 and 4 will illustrate the flexibility of the assembled racks with regard to use of space on the derrick floor. With the racks positioned in straight lines as shown in Figure 2, space adjacent the draw works 14 is conserved, this arrangement being preferable when the crew must work near the draw works. At times when operations are to be performed adjacent the rotary drilling unit, the racks can be positioned in a curved manner as in Figure

40 4, thus shortening the overall length of the racks, so that more room is provided adjacent the rotary drilling unit. These two arrangements of the racks are illustrative, and it will be evident that said racks may be arranged in various ways 45 on the derrick floor depending on circumstances.

The projections 28 may be of such size as to receive the collars of drill pipe or tubing, or if larger pipe is being stacked, they may be larger as necessary. Sockets may be provided 50 to receive solid rods, if such are used during any operations on the well.

By reason of the orderly stacking of the sections of pipe, the same sections of the pipe may be connected each time the pipe string is assembled going into the well. The orderly stacking of the pipe facilitates counting the sections as the pipe goes into or comes out of the well, so that the driller will always know how close he is to the bottom or the top of the well. More 60 orderly and faster running and removing of well pipe results from the use of this invention.

Various changes in the apparatus shown herein may be made without departing from the invention.

65 I claim:

1. A rack for supporting a heavy hollow metal oil well pipe in a substantially vertical position with its weight resting on its lower end, comprising a metal plate of sufficient strength to bear the weight of the heavy pipe and having means for positioning the open lower end of the pipe, and a substantially annular section of material on said plate adjacent said means to engage and protect the edge of the open end of the pipe, said material being relatively soft

with respect to the metal of said plate and pipe.

2. A rack for supporting sections of hollow pipe in substantially vertical position with the weight of the sections of pipe resting on the lower ends thereof, comprising a plurality of elongated metal plates adapted to be arranged on a base adjacent one another, said plates having a plurality of means each adapted to position the open lower end of a section of pipe, and means for adjustably securing said plates together at their ends, whereby adjacent plates may be adjusted with respect to one another on the base to arrange the sections of pipe as desired.

3. A rack for supporting heavy hollow oil well pipe in a substantially vertical position with the weight of the pipe resting on its lower end, comprising a metal plate of sufficient strength to bear the weight of the heavy pipe, means on said plate for positioning the open lower end of the pipe, said means having associated therewith a substantially annular band on said plate on which the lower end of the pipe rests, said band being made of material relatively soft with respect to the metal of the pipe, said plate having a drainage channel leading from within said band to provide for drainage from said pipe when the pipe is supported on said rack.

4. A rack for supporting heavy hollow pipe in a substantially vertical position with the weight of the pipe resting on its lower end, comprising a metal plate, an upstanding projection on said plate for receiving the open lower end of the pipe, a ring of metal on said plate surrounding said projection, on which ring the lower end of the pipe rests, said ring being made of metal relatively soft with respect to the metal of the pipe, said plate having an opening therein within said ring to provide for drainage from said pipe when the pipe is supported on said rack.

5. A rack for supporting heavy hollow pipe in a substantially vertical position with the weight of the pipe resting on its lower end, comprising a metal plate adapted to be positioned on a base, having means for receiving the lower open end of the pipe, said means including means engaging the lower end of the pipe to support the latter against lateral displacement and including a ring of metal on which the lower end of the pipe rests, said ring being made of metal relatively soft with respect to the metal of the pipe, said plate having an opening therein within said ring to provide for drainage from said pipe when the pipe is supported on said rack with its lower end received by said means, and means on said plate for spacing the lower face thereof adjacent said opening from said base, whereby matter draining from the pipe may be washed away from beneath said plate.

6. A rack for supporting sections of hollow pipe in a substantially vertical position with the weight of the pipe resting on its lower end, comprising an elongated metal plate adapted to be positioned on the derrick floor, spaced positioning means on said plate for individually receiving the open lower ends of sections of the pipe, said positioning means comprising upstanding projections of size for entry into the lower ends of the pipe, relatively soft metal rings surround-

ing said projections to engage and protect the edges of the open ends of the pipe, and a plurality of circularly spaced openings extending through the plate between said rings and said projections to provide for drainage from said pipe when the sections of pipe are supported on said rack, and means on said plate for spacing the lower face thereof from the derrick floor, whereby matter draining from the sections of pipe may be washed away from beneath said plate.

7. A rack for supporting sections of heavy hollow oil well pipe on the floor of a derrick with the sections in substantially vertical position with their weight resting on their lower ends, comprising a plurality of elongated plates of sufficient strength to bear the weight of the heavy pipe and adapted to be positioned adjacent one another in various convenient relations depending on the type of work being performed in the derrick, each of said plates having a series of spaced positioning means to individually position the open ends of sections of the pipe, said plates being adapted to be successively laid adjacent one another on the floor of the derrick and their positioning means successively supplied with the lower ends of sections of the oil well pipe as the latter is removed from the well and stacked in the derrick.

8. A rack for supporting sections of heavy hollow oil well pipe on the floor of a derrick in substantially vertical position with the weight of the sections of pipe resting on the lower ends thereof, comprising a metal plate of sufficient strength to bear the weight of the sections of pipe and having a plurality of positioning means each adapted to individually position the open lower end of a section of pipe, said positioning means being disposed on said plate closely adjacent one another to permit the stacking of the pipe in a minimum space in the derrick, said positioning means having bands of material relatively soft with respect to the metal of said plate associated therewith to engage and protect the edge of the open lower end of the sections of pipe.

9. A rack for supporting sections of heavy hollow oil well pipe on the floor of a derrick in substantially vertical position with the weight of the sections of pipe resting on the lower ends thereof, comprising a metal plate of sufficient strength to bear the weight of the sections of pipe and having a plurality of positioning means each adapted to individually position the open lower end of a section of pipe, said positioning means being disposed on said plate closely adjacent one another to permit the stacking of the pipe in a minimum space in the derrick, said plate having drainage channels associated with said pipe positioning means and leading from the interior of the sections of pipe when the latter are supported on said rack with their open lower ends engaged with said positioning means, said plate being provided adjacent said positioning means with material relatively soft with respect to the metal of said plate for protecting the edges of the open lower ends of the sections of pipe.

HAZEN L. RYMAL.
